UNITED STATES PATENT OFFICE

EUGENE S. TAYLOR, OF MONTPELIER, OHIO

DISPLAY TABLE

Application filed December 26, 1931. Serial No. 583,258.

The present invention relates to display tables and the like and means for supporting the vertical walls or partitions of the same; and its object is, generally, to provide improved means of this character for adjustably mounting such walls securely on the table.

This and any other and more specific objects hereinafter appearing are attained by, and the invention finds preferable embodiment in, the structure and parts particularly described in the body of this specification and illustrated by the accompanying drawing, in which:—

Figure 1 is a fragmentary top plan view of a table for displaying merchandise, and of a vertical partition wall thereof with its supporting or mounting means;

Figure 2 is a vertical sectional view thereof taken on line 2—2 of Figure 1;

Figure 3 is a vertical sectional view of the same taken on line 3—3 of Figures 1 and 2;

Figure 4 is a vertical sectional view showing a modified form of the structure taken on line 4—4 of Figure 5;

Figure 5 is a vertical sectional view thereof taken on line 5—5 of Figure 4; and

Figure 6 is a fragmentary top plan view of a corner portion of the structure showing the table and walls mounted thereon.

In the embodiment of the invention illustrated by these drawings, is shown a horizontal table or counter 1 for displaying articles of merchandise. This table is provided with sockets comprising spaced pairs of rectangular openings 2 cut through a metal strip or plate 3 embedded in the body portion 4 of the table and an elongated recess 5 in said body portion and extending beneath said strip, this strip overhanging this recess at the sides 16 of said openings.

Walls 6, some of which are partition walls as shown and which may be glass plates as indicated, are mounted in adjusted positions on the table to form compartments 7 for the merchandise articles. The walls are thus mounted vertically by means of posts 8 formed of springable sheet metal. These posts comprise a body portion or web portion 9, means for releasably holding the vertical edge portions 10 of the walls, and means for releasably securing or mounting the posts

on the table. Said means for holding the plates comprise, in the illustrated constructions, the opposite upper arms 11 and the opposite lower arms 12, the upper arms being desirably separated from the lower arms by gaps 13, as shown, for a purpose hereinafter explained.

The posts have also legs 14, extending downwardly and provided with oppositely or outwardly extending feet 15. The posts being formed of springable metal with the legs tending to spring apart, these legs may be sprung toward each other sufficiently to insert the feet into any pair of openings 2 respectively, whereupon the legs springing apart to the normal position shown in the drawing, the feet engage the under side of the strip 3 adjacent the sides 16 of the openings 2 and the legs in said openings hold the posts against horizontal movement.

The pair of opposite arms 11 engage the wall on its opposite sides and may be sprung apart to receive its vertical edge by inserting the same between them. It will thus be seen that although the legs 14 tend to spring apart in order to cause the feet to engage beneath the strip 3, the arms 11 spring toward each other to press on the wall and hold it in vertical position. That these arms and the legs may have this opposite spring action, the same are desirably separated by said gap 13, which may extend to the web portion 9 of the post as seen in Figure 3.

The legs and their feet may be formed in various shapes, as the curved form shown in Figures 4 and 5, and the form seen in Figures 2 and 3. These posts are adapted to holdingly support a flat wall as that seen in Figures 4 and 5, or a wall having a cross-sectionally enlarged lower edge portion 20 as that best shown in Figure 2, in which case such a wall is peculiarly well supported in vertical position by the upper arms 11 engaging the wall above said enlarged edge portion 20, and the lower arms 12 engaging said portion 20.

It will be seen that the pair of adjacent openings 2 receiving the legs of each post together with the recess 5, as shown in the views, form essentially a single socket, for

the portion 21 of the strip 3 between said pair may be omitted, thus forming such sockets as are seen at 2¹ in Figure 6.

The invention being intended to be pointed out in the claims, is not to be limited to or by details of construction of any particular embodiment thereof illustrated by the drawings or hereinbefore described.

I claim:

- 18 1. In combination: a table having a recess therein and a plate with spaced openings therethrough overlying the recess; a vertical wall; a post having means for releasably holding the wall, and legs spring-pressed apart and adapted to be thrust through the openings respectively in the sprung-together position of the legs and adapted to engage the under side of the plate in the normal position of the legs.
- 19 2. In combination: a table having a recess therein and a plate with openings therethrough overlying the recess; a vertical wall; a post having arms spring-pressed into releasable engagement with the wall between them, and legs spring-pressed apart and provided with outwardly extending feet adapted to be thrust into the openings in the sprung-together position of the legs and to engage the under side of the plate in the normal position of the legs.
- 20 3. In combination: a table having a recess therein and a plate with openings therethrough overlying the recess; a vertical wall having a cross-sectionally enlarged lower edge portion; a post having arms releasably embracing the wall above its said edge portion, and legs spring-pressed apart and provided with outwardly extending feet adapted to be thrust into the openings in the sprung-together position of the legs and to engage the under side of the plate in the normal position of the legs.
- 21 4. In combination: a table having a recess therein and a plate with openings therethrough overlying the recess; a vertical wall having a cross-sectionally enlarged lower edge portion; a post having arms spring-pressed to releasable engagement with the wall between them above its said edge portion, and legs spring-pressed apart and provided with outwardly extending feet adapted to be thrust into the openings in the sprung-together position of the legs and to engage the under side of the plate in the normal position of the legs.
- 22 5. In combination: a table having a recess therein and a plate with openings therethrough overlying the recess; a vertical wall having a cross-sectionally enlarged lower edge portion; a post having arms spirng-pressed to releasable engagement with the wall between them above its said edge portion, and legs spring-pressed apart and provided with outwardly extending feet adapt-

sprung-together position of the legs and to engage the under side of the plate in the normal position of the legs, there being gaps between the arms and the legs permitting their oppositely spring-pressed movement.

6. In combination: a table having a recess therein and a plate with openings therethrough overlying the recess; a post having arms connected at one vertical side thereof spring-pressed to releasable engagement with the wall between them, and legs spring-pressed apart and provided with feet adapted to be thrust into the openings in the sprung-together position of the legs and to engage the under side of the plate in the normal position of the legs.

7. In combination: a table having a recess therein and a plate with openings therethrough overyling the recess; a vertical wall having a cross-sectionally enlarged lower edge portion; a post having upper arms spring-pressed to releasable engagement with the wall between them above its said edge portion, lower arms embracing said edge portion, and legs spring-pressed apart and provided with outwardly extending feet adapt-

ed to be thrust into the openings in the sprung-together position of the legs and to engage the under side of the plate in the normal position of the legs.

8. In combination: a table having a recess therein and a plate with openings therethrough overlying the recess; a vertical wall having a cross-sectionally enlarged lower edge portion; a post having upper arms spring-pressed to releasable engagement with the wall between them above its said edge portion, lower arms embracing said edge portion, and legs spring-pressed apart and provided with outwardly extending feet adapted to be thrust into the openings in the sprung-together position of the legs and to engage the under side of the plate in the normal position of the legs.

9. In combination: a table having sockets with overhanging side walls, the sockets being spaced apart in the lateral direction of the hereinafter-mentioned wall; a vertical wall; a post having means for releasably holding the wall, and legs spring-pressed apart and provided with outwardly extending feet, the legs being adapted to be thrust into the sockets in the sprung-together posi-

tion of the legs and in their normal position in the sockets engaging the walls thereof to hold the post against horizontal movement, and the feet in said normal position engaging said overhanging side walls to hold the posts against accidental removal from the sockets.

10. In combination: a table having spaced sockets; a vertical wall; a post having means in spring-pressed relation with the wall for releasably holding the same, and legs spring-

pressed apart and adapted in their sprung-together position to be thrust into the sockets respectively and to releasably engage the same respectively in the normal position of
5 the legs.

In testimony whereof I have hereunto set
my hand at Montpelier, Ohio, this 19th day
of December, 1931.

EUGENE S. TAYLOR.
